CABLE TERMINAL FOR BATTERY POSTS

Manuel M. Pontus, East Providence, R. I.

Application May 14, 1932, Serial No. 611,317

6 Claims. (Cl. 173—259)

This invention relates to a cable terminal for a battery post and has for one of its objects to provide a construction which may be securely fastened to the post and yet easily released therefrom even though there be corroding about the contacting parts.

Another object of the invention is the provision of a terminal having an opening to receive the post so shaped that the wall of the opening at one end will engage with the post about substantially one-half of the circumference of the post and will be held in firm contact therewith by a threaded member extending through the opposite wall and engaging the diametrically opposite side of the post, the end of the opening opposite that engaged being enlarged to loosely receive the post for releasing the same from contacting engagement prior to lifting the terminal from the post.

Another object of the invention is the provision of a wear or clamp plate which will be continually held in a desired position and may not become separated or lost from the terminal.

With these and other objects in view, the invention consists of certain novel features of construction, as will be more fully described, and particularly pointed out in the appended claims.

Fig. 1 is a top plan view of my terminal mounted on a fragmental portion of a battery.

Fig. 2 is a sectional view on line 2—2 of Fig. 1.

Fig. 3 is a perspective view of the wear plate.

Fig. 4 is a perspective view of the body member of the terminal.

Fig. 5 is a sectional view of a modified form of threaded securing means for binding the cable in position.

It is found desirable in the use of cables and terminals for securing them in position to provide a construction which may, by tapping, be released even though there be corrosion on the engaging parts tending to cause them to adhere together, which I have accomplished by providing an egg-shaped opening. Also I have provided a wear plate which may conform to the shape of the terminal and which will be held in position by engaging the binding screw and thus is not capable of being separated or lost; and I have also so arranged the arm for receiving the cable that it will be held in place without the use of solder or threaded means; and the following is a detailed description of the present embodiment of this invention illustrating the preferred means by which these advantageous results may be accomplished.

With reference to the drawing, 10 designates a fragmental portion of a battery having a post

11 which is slightly tapered in form as illustrated at 12. The terminal has a body portion 13 provided with an orifice 14 of generally egg-shape outline, with a smaller end 15 and a large end 16, the small end being of a size to engage the post 11 about substantially one-half of its circumference with its walls tapered to fit the tapered post as illustrated in Fig. 2. Where, however, a straight post is used the wall will be formed to correspond and fit the same. The large end of the body is 10 of a size to freely encircle the post therein and permit the body to be lifted easily therefrom.

A wear plate 17 is positioned in the orifice 14 and is of a length greater than the thickness of the body 13 to project therethrough to facilitate 15 its position and this wear plate may be provided with an arm 18 which extends out of the orifice and longitudinally thereof with a ring-shaped end 19 through which a bolt 20 extends and has threaded engagement with the opening 21 in the 20 wall of the body. This bolt extends longitudinally of the orifice and engages the wear plate 17 to force it into engagement with the post. And the bolt is also provided with a head 22, the surface 25 beneath the head having a bearing in the ring shaped end 19 and against which ring the under surface of the head engages. This arrangement makes the wear plate 17 a unitary structure with the other elements of the terminal. In some cases I may use a bolt 32 and a threaded opening 30 33 to bind the cable 25 in position over the shoulder 31.

The foregoing description is directed solely towards the construction illustrated, but I desire it to be understood that I reserve the privilege 35 of resorting to all the mechanical changes to which the device is susceptible, the invention being defined and limited only by the terms of the appended claims.

I claim:

1. A terminal for securing a cable to a battery binding post comprising a body member having an elongated orifice of generally egg-shape to receive the binding post of a battery, means for connecting said member to a cable, a set screw extending through said member into said orifice and generally longitudinally thereof for forcing the post against the end wall of said orifice, said orifice being smaller at its end distant from said set screw.

2. A terminal for securing a cable to a battery binding post comprising a body member having an elongated orifice of generally egg-shape with its side walls spaced apart a distance substantially equaling the diameter of the binding post at its 55

- small end and tapering to space the side walls a distance substantially greater than the diameter of the post at its larger end, and a set screw extending through said body member into said orifice at the large end thereof directed generally longitudinally thereof for forcing the post against the end wall of said orifice.
3. A terminal for securing a cable to a battery binding post, comprising a body member having an elongated orifice therein for receiving a binding post, a wear plate in said orifice for engaging the binding post, a set screw through said member for forcing said plate against the binding post, an arm on said plate, said arm extending horizontally outwardly from the top of said wear plate a substantial distance, and a ring shape portion on said arm for engaging the inner surface of the head of said set screw and through which said set screw extends.
4. In a wear plate construction, a plate having a curved section, an arm integral with said plate and extending from one edge thereof and at right angle thereto, said arm being of substantially the same thickness as that of said plate, and of smaller width than that of the plate, said arm also having a substantial length, an enlarged circular portion at the end of the arm away from

the plate and extending in the same direction as and parallel to the said plate, and a circular opening in said portion of the arm.

5. A terminal for securing a cable to a battery post, comprising a member having an elongated opening therein for receiving the post, an arcuate wear plate receivable in said opening and adapted to engage with the post to force the same towards one end of said opening, means for adjusting said plate longitudinally of said opening and an extension on said plate projecting beyond said member whereby the plate may be grasped to position it relatively to said member.

6. A terminal for securing a cable to a battery post, comprising a member having an elongated opening therein for receiving the post, a set screw in said member extending through said member and longitudinally of said opening, an arcuate wear plate of a length greater than the length of the corresponding dimension of the member through which said opening extends and positioned in said opening and extending therebeyond a sufficient distance to be grasped and held, said set screw engaging said plate to force it against the battery post when inserted in said opening, and means for connecting said member to a cable.

MANUEL M. PONTUS.
